troleum Company, a corporation of Delaware
Filed Dec. 12, 1960, Ser. No. 75,364
4 Claims. (Cl. 55—40)

This invention relates to deoiling of cracking furnace effluents. In one aspect it relates to deoiling of cracked gases resulting from cracking of ethane and of propane in the production of ethylene. In another aspect it relates to the removal from cracking furnace effluents of materials which tend to polymerize and deposit on equipment surfaces.

The presence of polymerizable material in hydrocarbon cracking furnace effluents is well known in the hydrocarbon cracking art. Polymerizable materials react at elevated temperatures to produce polymers, some of which are liquid and some of which are solids. It is the solid polymer material which causes trouble and expense because it deposits on such heat exchange equipment as reboiler tubes, and on the walls of reboilers and fractional distillation columns, particularly in the kettle section thereof, in pipes and in other equipment contacted by fluids containing these polymer forming materials. Coatings of solid polymer effectively interfere with heat transfer thereby reducing the efficiency of the heat exchange equipment. In the cracking of ethane and propane for production of ethylene such polymerizable materials form.

It is one object of this invention to provide a process for the removal of oils containing the above-mentioned polymerizable material from cracking furnace effluents. Another object of this invention is to provide a process for removal of polymerizable material from cracking furnace effluents to eliminate solid polymer formation and deposition on heat exchange equipment. Still another object of this invention is to provide a process for removal of polymer-forming material from cracking furnace effluents resulting from the cracking of ethane and of propane in the production of ethylene. Yet another object of this invention is to provide a process for removal of undesirable high boiling oils including aromatic and polymerizable materials from ethane and from propane cracking furnace effluents. Still other objects and advantages will be realized upon reading the following description which, taken with the attached drawing, forms a part of this specification.

In cracking ethane comparatively small amounts of heavy material are produced. As a result less heavies removal from the ethane cracking effluent is required than from the propane cracking effluent. It would not be feasible to send the cracking effluents from both the ethane and the propane cracking operations to the deoiler even if the deoiler had sufficient capacity to handle both streams. Separate absorbers are used because the two cracking furnace effluents have unlike compositions.

Since the absorption oil must be recovered from the rich absorbent from the ethane cracking effluent absorber and since this stream is small it is advantageously deoiled in the deoiler treating the effluent from the propane cracking operation. Operating in this manner then permits recovery of absorption oil and removal of heavy materials from both ethane and propane cracking effluents in a single deoiling and stripping operation.

The drawing illustrates in diagrammatic form an arrangement of apparatus for carrying out the process and achieving the objects of this invention.

In the drawing reference numeral 42 identifies a conduit leading from a source of ethylene to apparatus 41. This apparatus identified by reference numeral 41 illus-

2

trates the processing of ethane which involves cracking of an ethane-containing charge stock, quenching the effluent of the cracking operation and compressing the quenched effluent. Thus, the cracked, quenched, and compressed effluent from the cracking operation passes from apparatus 41 through a conduit 7 into the lower portion of an absorber 8. This absorber is termed herein "heavy ends absorber." In this absorber a relatively small volume of an absorption oil enters the top of the absorber through a conduit 30 and flows downward in contact with up-flowing vaporous or gaseous material from conduit 7. This heavy ends absorber is provided with efficient vapor-liquid contact promoting apparatus such as bubble cap trays. The volume of absorbent flowing downward through this absorber is intended to be sufficiently small that it absorbs mainly the heavy and high boiling ends, that is, high boiling oils and the polymer-forming materials from the charge gases without substantial absorption of the normally gaseous materials. Effluent and unabsorbed gases from absorber 8 leave this vessel by way of conduit 9 for subsequent treatment as desired.

A conduit 44 conducts propane from a source, not shown, to a system of cracking, quenching and compression identified by reference numeral 43. This apparatus 43 is quite similar to that identified by reference numeral 41, the difference being that the cracking furnace of apparatus 43 is designed for and operated under conditions suitable for the cracking of propane to produce ethylene. The effluent from the cracking, quenching, the compression system 43 is passed through a conduit 17 into the lower portion of an apparatus herein termed a deoiler and identified by reference numeral 18. The upper portion of this deoiler is actually an absorption column more or less similar to absorber 8. This deoiler is provided with efficient vapor-liquid contact promoting packing such as bubble cap trays. An absorption oil or absorbent is introduced into the upper portion of deoiler 18 through a conduit 29. Unabsorbed gases leave deoiler 18 through a conduit 28 for such disposal, as desired. In addition to the introduction of lean absorbent through conduit 29 into the upper portion of the deoiler 18, the rich absorbent from the bottom of absorber 8 passes through a conduit 10 into the deoiler at about its mid-section, vertically. Thus this rich absorption oil from absorber 8 is mixed with the absorbent introduced through conduit 29 and the combined liquid flows on down and into a reboiler section 11. This reboiler section 11 involves the use of a reboiler heat exchanger 13 which heats the rich absorption oil from the lower portion of the reboiler section 11 and allows a portion of this heated rich absorption oil to pass through a conduit 14 into the lower portion of section 11. Thus the heated rich absorption oil re-entering the lower portion of section 11 reboils this section of the column. The more volatile of the absorbed materials vaporized from the absorption oil assists in stripping the light ends from the downflowing combined absorbents flowing downward in sections 11 and 18. The downflowing absorbent in column 8 is intended to absorb polymeric material formed during cracking of the ethane in apparatus 41 and the downflowing absorbent in deoiler 18 is intended to absorb substantially the same constituents from the propane cracking operation. It is realized that other materials besides those desired to be absorbed will be absorbed in such absorption equipment.

In one mode of operation it is preferred to use only a very small stream of absorbent in absorber 8 so that substantially only the highest boiling constituents will be absorbed. In deoiler 18 a sufficiently large flow of absorbent is introduced through conduit 29 as to act as a reflux and cool the top of this deoiler to promote absorp-

tion and to assist in retarding loss of absorbent with the unabsorbed gases.

The bottoms from the reboiled absorber 11 leave this vessel via conduit 19 for passage into a depentanizer column 20. Heat for reboiling is introduced into this column by way of a conduit 35. This heat may be in the form of superheated steam passing through a heating coil, not shown, in the kettle section of column 20 or outside the column as reboiler 13, or this heat can be in the form of open steam added directly into the kettle section of the column. Pentane and lower boiling materials are passed overhead through a conduit 26 from column 20, condensed in a condenser 27, said condensate passing into an accumulator tank 23. A valved conduit 34 communicates with the accumulator tank in case pressure relief is necessary. A portion of the condensate from accumulator 23 required for refluxing column 20 is passed through a conduit 33 into the upper section of the column while the remainder is passed through a line 22 as a product of the system, for such disposal as desired. The depentanized bottoms material from depentanizer 20 are removed therefrom through a conduit 21 and are passed into an absorption oil re-run still 32. This still is operated in such a manner as to distill overhead the absorption oil introduced subsequently through conduits 29 and 30 into the absorbers. In other words, still 32 is an absorption oil purification still. The vaporous absorption oil or absorbent is passed from the still through an overhead conduit 25, the material is condensed in a condenser 36 and condensate is passed on into an accumulator tank 40. The condensate is pumped through a conduit 37 by a pump 38, the condensate or absorbent oil being cooled in a cooler 12 and chilled in a chiller 16 prior to introduction through conduits 29 and 30 into the respective absorbers. Heat for reboiling the kettle section of still 32 is introduced therewith through a conduit 39 from a source, not shown. Preferably steam from conduit 39 passes through a heat exchange coil in the kettle section of still 32 so as not to introduce water into the contents of the still. Bottoms product from still 32 is removed from the still through a conduit 24 for such disposal as desired. This bottoms material while identified in a table given hereinafter as C_6^+ is actually material boiling higher than the ab-

20. In this case the remainder of this bottoms material, that is from 90 to 50 percent is passed through conduit 45 and added to the purified absorbent flowing through conduit 37. By distilling a substantial fraction of the 5 depentanizer bottoms the concentration of high boiling polymers and polymer-forming materials in the depentanizer bottoms is maintained at a sufficiently low level and thus polymer formation on high temperature spots in this apparatus is maintained at a minimum.

10 Steam for heating reboiler 13 is passed thereto through a conduit 15 from a source, not shown. This reboiler is a closed coil heat exchanger for the purpose of maintaining the absorbent in substantially a moisture-free condition. A conduit 31 communicates with accumulator tank 40 for addition of make-up absorbent as required.

15 In one instance a benzene-rich absorption oil boiling from about 180° to about 360° F. was used as an absorption oil for this operation. This absorbent contained approximately 80 weight percent benzene. In this case 20 the absorption oil re-run still 32 was operated in such a manner as to withdraw bottoms material through conduit 24 having an initial boiling point of approximately 230° F. In one instance this bottoms material had a 25 boiling range of approximately 230° to about 432° F. With the use of a benzene-rich absorbent with the removal of bottoms material from re-run still 32 having a boiling range of from about 230° to about 432° F. the temperatures and pressures employed in the system are those illustrated in the drawing.

30 It is realized by those skilled in the art that the temperatures given in the drawing can be varied within limits by varying the pressures at the various process points accordingly.

35 Cooler 12 can, if desired, employ plant cooling water as a coolant. For further cooling or chilling the effluent from cooler 12, a refrigerated cooler or chiller 16 is required. This refrigerated chiller or cooler can involve use of a propane refrigeration cycle. An ammonia refrigeration system also can be used in place of propane if desired.

40 The following tabulation illustrates product compositions at various process points of the system. The column headings in the table are found on the drawings as the corresponding reference numerals.

sorption oil. This bottoms material is actually polymers and even some high boiling non-polymeric hydrocarbons.

A by-pass conduit 45 is shown connecting conduit 21 with conduit 37. This connection is made just upstream of cooler 12 as regards the direction of flow of lean absorbent in conduit 37. This by-pass conduit is provided in case it is not desired to distill the entire volume of depentanized absorption oil from the bottom of depentanizer 20. In many instances it may be sufficient to distill in re-run still 32 from, for example, 10 to 50 percent of the depentanized bottoms from depentanizer

65 Such auxiliary apparatus as valves, pressure indicating, recording and control equipment, temperature indicating, recording and controlling equipment are not shown for purposes of simplicity and brevity. The need for such auxiliary equipment, its installation and maintenance are 70 well understood by those skilled in the art.

While the above flow diagram has been described for illustrative purposes, the invention obviously is not limited thereto.

We claim:

75 1. A process for separating into different hydrocarbon

fractions first and second gas streams of different compositions and each containing substantial proportions of C₁ and C₂ and heavier hydrocarbons which comprises the steps of:

- (1) absorbing heavier hydrocarbons from said first stream in an absorbent in a first absorption zone while leaving substantially all of the C₁ and C₂ hydrocarbons unabsorbed;
- (2) passing said C₁ and C₂ hydrocarbons overhead as a first overhead fraction while recovering rich absorbent containing heavier hydrocarbons as a first bottoms fraction;
- (3) absorbing heavier hydrocarbons from said first bottoms fraction and from said second stream in an absorbent in a second absorption zone as a second bottoms fraction while leaving substantially all of the C₁ and C₂ hydrocarbons in said second stream unabsorbed;
- (4) passing the C₁ and C₂ hydrocarbons of step (3) overhead as a second overhead fraction;
- (5) separating said heavier hydrocarbons from said second bottoms fraction to separately recover lean absorbent and heavier hydrocarbons;
- (6) passing lean absorbent from step (5) to steps (1) and (3) as said absorbent; and
- (7) recovering as products the first and second overhead fractions of steps (2) and (4) and the heavier hydrocarbons of step (5).

2. The process of claim 1 wherein the gases contacted in said first and second absorption steps are gaseous effluents of hydrocarbon cracking operations and said absorbent is an aromatic liquid boiling within the range of about 175° F. to 225° F.

3. The process of claim 1 wherein said first stream is an effluent from ethane cracking containing substantial proportions of ethylene, said second stream is an effluent from propane cracking also containing substantial proportions of ethylene, and said absorbent is an aromatic liquid boiling within the range of about 175° F. to about 225° F.

4. The process of claim 1 wherein said streams contain heavier hydrocarbons higher boiling and lower boiling than said absorbent; and step (5) comprises the steps of distilling the lower boiling hydrocarbons from said absorbent and thereafter distilling the lean absorbent from the residue.
